UNITED STATES PATENT OFFICE.

LEWIS S. CHILSON, OF ATTLEBORO, MASSACHUSETTS, ASSIGNOR TO J. M. FISHER COMPANY, OF ATTLEBORO, MASSACHUSETTS, A CORPORATION OF RHODE ISLAND.

EXTENSION DEVICE FOR BRACELETS.

Application filed August 3, 1926. Serial No. 126,817.

This invention relates to an extension device for bracelets more particularly watch bracelets for holding a wrist watch to the arm of the wearer; and the object of this 5 invention is to provide a plurality of sections hinged together to be folded one upon the other to make the bracelet of a size to snugly fit the wrist of the wearer and which may be unfolded to extend the length of the 10 bracelet to permit it to be withdrawn from the arm of the wearer without detachment of any of the parts.

A further object of this invention is to provide a means to adjust the effective working length of the bracelet when on the arm 15 of the wearer.

A still further object is to provide a pin extending through the side walls of the device to be manually engaged and moved to 20 initially open or unfold one of the sections relative to another.

With these and other objects in view, the invention consists of certain novel features of construction, as will be more fully described, and particularly pointed out in the 25 appended claims.

In the accompanying drawings:

Figure 1 is a side elevation illustrating the improved device in its relation to a wrist 30 watch bracelet.

Figures 2, 3 and 4 are perspective views of the different sections of the device.

Figure 5 is a central sectional elevation of the device in closed position.

Figure 6 is a central sectional plan view of the device looking from the bottom thereof.

Figure 7 is a sectional elevation taken on line 7—7 of Figure 6.

Figure 8 is a central sectional elevation of the device in extended position.

Figure 9 is a plan view of the device with the sections extended as shown in Figure 7.

Figure 10 is a perspective view showing the device with the sections partially folded.

It is found desirable in bracelet construction especially watch bracelets to provide a device interposed between the ends of the watch bracelet by which the effective working length of the bracelet for holding the watch snugly on the wrist may be extended to permit the bracelet to be passed over the hand of the wearer without detaching any

of the parts from each other or from the watch. It is also found desirable to provide means in the extension members by which the effective working length of the bracelet may be adjusted when on the arm of the wearer to snugly fit different sized arms and the following is a detailed description of the present embodiment of my invention and showing one construction of extension member by which these advantageous results may be accomplished:

With reference to the drawings, 10 designates a wrist watch and 11, 12 parts of the watch bracelet for holding the watch onto the arm of the wearer. These parts are each provided at one end with hooks 13 for engaging the bails 14 of a wrist watch 70 and interposed between their opposite ends 15 and 16 there is an extension device 17 which is composed of a plurality of sections 18, 19 and 20 hinged together and foldable one upon the other.

The bottom section 18 is provided with a bottom wall 21 and side walls 22 which are longitudinally slotted as at 23 and slidable in this slot is a pin 24 to which the end 15 of the bracelet part 11 is attached.

The intermediate section 19 is hinged to the end section 18 by means of openings 24, 25 and pins 26, as illustrated in Figure 9. The side walls of the section 27 are spaced apart by cross bars 28, a sufficient distance 85 to be folded and fit within the side walls of the section 18.

A series of notches 28 are provided in each of the side walls 27 of the intermediate section 19 which are adapted to engage the pin 90 24 to hold the same in different adjusted positions relative to these two sections. Each of the notches is inclined so that a tension on the bracelet part 15 attached to the pin 24 serves to draw the same into the 95 notches rather than to move the pin to released position.

The pin 24 is provided with heads 29 which may be manually engaged to slide the pin towards the hinge connection 24—25 100 100 which serves to swing the section 19 upon its pivots 26 in initially opening the extension device.

The top section 20 is hinged to the intermediate section 19 by means of openings 105 30, 31 and pivots 32 and comprises a top

wall 33 with side walls or flanges 34 which are of a sufficient distance apart to engage the outer side of the walls 22 of the bottom section when the sections are in folded relation.

Ears 35 are provided at the free end of the top section 20, which ears have openings 36 for receiving means for attaching the end 16 of the bracelet part 12 thereto. These 10 ears 35 are so positioned relative to the end cross bar 28^a of the intermediate section that they snap over and frictionally engage this cross bar, as illustrated in Figure 5, to releasably retain the top section in folded 15 closed position.

It will thus be seen that I have provided an extendible device which may be folded upon itself to fit snugly about the wrist and retain a wrist watch in the desired position 20 and yet one which may be unfolded to permit the watch to be withdrawn over the hand without detaching any of the parts, the initial movement of extension being by means of knobs or heads on the pin 24 to be 25 slid longitudinally of the device. It will also be seen that I have provided a means by which the effective working length of the bracelet may be adjusted when on the wrist of the wearer by simply moving the adjusting pin by means of the knobs or heads at its ends.

The foregoing description is directed solely towards the construction illustrated, but I desire it to be understood that I reserve 25 the privilege of resorting to all the mechanical changes to which the device is susceptible, the invention being defined and limited only by the terms of the appended claims.

I claim:

- 40 1. A wrist watch bracelet having two strap parts, two sections hinged together and having means connecting their ends to the ends of said strap parts, one of said sections having side walls, spaced cross bars 45 connecting said walls, and means on the other of said sections for snapping over and frictionally engaging one of said cross bars for holding said sections in folded-over closed position.
- 50 2. An extendible member for a bracelet, including sections having side walls hinged together, formations in the side walls of said sections, a pin engaging said formations and extending outwardly through the 55 side walls of said sections to be manually engaged, said pin and formations co-operating to cause said sections to initially swing apart in moving the device to extended position upon movement of said pin relative to said formations.
- 60 3. An extendible device for a bracelet or

the like including connected sections, one of said sections having side walls with slots therein, a pin slideable in said slots, and adapted to be connected to a bracelet, another of said sections hinged to said slotted section and having side walls with spaced notches to engage said pin in various different positions of adjustment.

4. An extendible device for a bracelet or 70 the like including a section having side walls with slots therein, a pin slideable in said slots, and adapted to be connected to a bracelet, a section hinged to said first section and having inclined notches in its side 75 walls to receive said pin to secure said sections together when in closed working position said pin being slideable in said slot and notches to cause said sections to initially swing apart in moving the device to extended 80 position.

5. In a wrist watch attachment having two strap parts, an extendible device comprising end sections, means for securing one of said strap parts to one end section, an intermediate section hingedly connected at its opposite ends to said end sections whereby said sections may be folded one upon the other, means for securing the other strap part to the other end section and formations on one of the said end sections and said intermediate section cooperating with said strap securing means for adjusting and securing the effective folded or working length 95 of one of said strap parts, and frictional means between the intermediate section and one of said other sections for securing them in closed position.

6. A wrist watch bracelet having two parts, an extendible device comprising an end section having a bottom wall with slotted side walls, a pin having one of the bracelet parts connected thereto and slideable in the slots of said side walls, an end section having a top wall and side walls to slideably engage said slotted side walls and having the other bracelet part connected thereto, an intermediate section hinged at its opposite ends to said end sections and having side walls with spaced inclined notches and cross bars connecting said walls, said notches being engageable with said pin in different positions of said pin along said slots whereby to adjust the working length 105 of the bracelet and secure the intermediate section in folded position, and frictional means on one of the end sections for engaging the cross bar of the intermediate section to secure it in folded position.

In testimony whereof I affix my signature.

LEWIS S. CHILSON.
